CLAIM

The ornamental design for a mount for attaching a sighting aid to a rifle or shotgun, as shown and described.

DESCRIPTION

FIG. 1 is a perspective view of a mount for attaching a sighting aid to a rifle or shotgun, showing my new design;

FIG. 2 is a front elevational view, the rear being a mirror image thereof;

FIG. 3 is a bottom plan view thereof;

FIG. 4 is a left side elevational view thereof;

FIG. 5 is a right side elevational view thereof;

FIG. 6 is a top plan view thereof;

FIG. 7 is a perspective view of a second embodiment;

FIG. 8 is a front elevational view, the rear being a mirror image thereof;

FIG. 9 is a top plan view thereof;

FIG. 10 is a left side elevational view thereof;

FIG. 11 is a right side elevational view thereof; and,

FIG. 12 is a bottom plan view thereof.
